CLAIM

The ornamental design for an electronic thermometer as shown and described.

DESCRIPTION

FIG. 1 is a front, left and top perspective view of an electronic thermometer, showing my design.

FIG. 2 is a rear, right and bottom perspective view thereof of the electronic thermometer.

FIG. 3 is a front elevation view thereof of the electronic thermometer.

FIG. 4 is a rear elevation view thereof of the electronic thermometer.

FIG. 5 is a left side elevation view thereof of the electronic thermometer.

FIG. 6 is a right side elevation view thereof of the electronic thermometer.

FIG. 7 is a top plan view thereof of the electronic thermometer; and,

FIG. 8 is a bottom plan view thereof of the electronic thermometer.

The dashed broken lines depict portions of the electronic thermometer that form no part of the claimed design.
